UNITED STATES PATENT OFFICE.

HAROLD J. HANSEN, OF LA CROSSE, WISCONSIN.

PRIMING DEVICE FOR MOTOR-VEHICLE ENGINES.

1,115,814.

Specification of Letters Patent.

Patented Nov. 3, 1914.

Application filed June 18, 1914. Serial No. 844,986.

To all whom it may concern:

Be it known that I, HAROLD J. HANSEN, a citizen of the United States, residing at La Crosse, in the county of La Crosse and State of Wisconsin, have invented certain new and useful Improvements in Priming Devices for Motor-Vehicle Engines, of which the following is a specification, reference being had to the accompanying drawings.

This invention relates to an improved priming device for motor vehicle engines, whereby the engine may be easily and quickly started without requiring the laborious cranking of the engine shaft which must usually be resorted to.

In its more specific aspect the invention contemplates the provision of a gasolene supply tank or reservoir mounted at any convenient place upon the car body, an air supply tank connected to said reservoir and means for controlling the supply of air thereto, and means for discharging air and gasolene in proper proportions to the spark plugs of the several engine cylinders.

The invention has for a further object to generally improve and simplify the construction of devices of the above character whereby the starting of the engine is assured with but little labor on the part of the operator.

With the above and other objects in view, the invention consists in novel features of construction, combination, and arrangement of parts as will be hereinafter referred to and more particularly pointed out in the specification and claims.

For a full understanding of the invention, reference is to be had to the following description and accompanying drawing, in

which—
Figure 1 is a side elevation of an engine priming device constructed in accordance with my invention; Fig. 2 is a section taken on the line 2—2 of Fig. 1; and Fig. 3 is a horizontal section taken on the line 3—3 of Fig. 2.

Referring in detail to the drawing, 5 designates a tank or reservoir to receive the gasolene, said tank being provided at its lower end with a supply pipe 6 extending to a main supply tank, said pipe having a suitable valve 7 arranged therein. The top of this tank is also provided with an opening closed by a threaded cap 8 whereby the air may be released from the tank when it is desired to fill the same.

9 designates an air tank provided with a valve 10 of any ordinary or improved form to which a pump is adapted to be attached. The top of this tank is equipped with a suitable air gage 11. The gasolene tank 5 and the air tank 9 are provided at their upper ends with nipples indicated at 12 and 13 respectively, which are connected by a hose or tube 14. A valve 15 is arranged in the nipple 14 whereby the supply of air from the tank 9 to the gasolene tank 5 may be controlled and regulated.

The pipe 16 extends vertically and downwardly through the top of the gasolene tank 5 and has its lower open end spaced from the bottom of said tank. The upper end of this pipe exteriorly of the tank 5 is horizontally extended as shown at 17 and provided with a valve 18. A chambered head 19 is detachably mounted upon the end of this horizontal portion 17 of the pipe and in opposite sides thereof sleeves 20 are threaded. These sleeves carry tubes 21 which extend to the spark plugs of the engine cylinders or suitable valves arranged therein as will be readily understood, said tubes supplying a mixture of gasolene and air directly to the ignition electrodes.

A short pipe 22 also extends downwardly from the horizontal portion 17 of the pipe 16 and enters the upper end of the gasolene tank 5. In this pipe, and the upper end of the vertical portion of the pipe 16, valve plugs indicated at 23 and 24 respectively are threaded. Each of these plugs is cut away or recessed on one side as at 25 so that by turning the same, the volume of gasolene or air passing through the pipes may be regulated as will be readily understood.

Having above described the several structural features of my invention, its operation will be understood as follows: Assuming that the tank 9 has been supplied with air and the gasolene tank 5 partially filled with gasolene, the operator quickly opens and closes the needle valve 15, thus allowing the air to pass through the tube 14 and into the upper end of the tank 5. The pressure of this air acting upon the gasolene forces the same upwardly through the vertical pipe 16. The valves 23 and 24 are adjusted so that air will enter from the upper end of the tank 5 into the horizontal portion 17 of the pipe 16 and mix with the gasolene flow. The valve 18 is, of course, opened to permit the passage of this

mixture into the head 19, from which it is conducted by the tubes 21 to the several engine cylinders. The valve 18 when closed will prevent any possibility of the gasoline 5 in the tank 5 being exploded by back fire from the engine cylinders, though such possibility is extremely remote. Therefore, when the invention is not in use, this valve is closed, and it is unnecessary to close the 10 valve members 23 and 24.

From the foregoing description taken in connection with the accompanying drawing, the construction, manner of operation, and several advantages of my invention will be 15 clearly and fully understood. In order to start the operation of the engine, the several valves are properly adjusted, and the mixture forced under pressure to the several engine cylinders. The crank of the engine 20 is given a turn of about 90° so that the same is off of a dead center, and by operating the magneto switch to close the battery circuit, the mixture of gasoline and air is ignited to explode the charges in the engine cylinders. 25 Thus the immediate starting of the operation of the engine without the usual laborious cranking is assured. The device as a whole consists of comparatively few parts which are all of very simple form, and it 30 will therefore be appreciated that the invention may be produced at small manufacturing cost.

While I have above described the preferred form, construction, and arrangement 35 of the several elements employed, it will be understood that the device is, nevertheless, susceptible of considerable modification therein, and I therefore reserve the privilege of resorting to all such legitimate changes 40 as may be fairly embodied within the spirit and scope of the invention as claimed.

What is claimed is:

1. In a priming device, the combination

of a gasoline tank, an air tank, a pipe connecting the upper ends of said tanks and a 45 valve therein to control the supply of air to the gasoline tank, a pipe extending downwardly through the top of the gasoline tank and having its lower open end spaced from the bottom thereof, a chambered head 50 threaded upon the upper end of said pipe, conducting tubes mounted in opposite sides of said head, an air supply pipe connected to said last named pipe and to the top of the gasoline tank, and valves in said pipes to 55 regulate the supply of gasoline and air to said chambered head.

2. In a priming device, a gasoline tank, an air supply tank, a pipe connecting the upper ends of said tanks and having a valve 60 arranged therein to control the supply of air to the gasoline pipe, a pipe extending downwardly through the top of the gasoline tank and having its lower open end spaced from the bottom thereof, the upper end of said 65 pipe exteriorly of the tank being horizontally disposed and provided with a cut-off valve, a chambered head threaded upon the end of said horizontal portion of the pipe, conducting tubes mounted in opposite sides 70 of said head, a pipe connected to the horizontal portion of said last named pipe and extending through the top of the gasoline tank to admit air to said first named pipe at a point between the valve therein and the 75 point at which said pipe enters the top of the tank, and valves arranged in said air and gasoline pipes to control the supply to said chambered head.

In testimony whereof I hereunto affix my 80 signature in the presence of two witnesses.

HAROLD J. HANSEN.
